[57] CLAIM

The ornamental design for a bottle container, as shown.

DESCRIPTION

FIG. 1 is a top front perspective view of a bottle container showing my new design;

FIG. 2 is a rear bottom perspective view thereof;

FIG. 3 is a front elevational view thereof, the rear being identical;

FIG. 4 is a top plan view thereof;

FIG. 5 is a side elevational view thereof, the opposite side being identical; and

FIG. 6 is a cross-sectional view thereof taken in the direction of the arrows on line 6—6 of FIG. 4.
